INSOLE FOR SHOES

Martin Shapiro, Bronxville, N. Y.

Application January 15, 1948, Serial No. 2,491

1 Claim. (Cl. 36—71)

1

The object of this invention is to provide an improved insole adapted to be built into a shoe as an integral part thereof, or the insole may be used as a separate article to be placed within a shoe upon the regular insole thereof.

The insole according to this invention is characterized by the provision of means for holding the metatarsal and tarsal bones in their natural positions and allows the metatarso-phalangeal joints to drop gently and naturally under weight bearing into a resilient cushion insole portion whereby shocks and irritation are avoided or alleviated, and whereby the natural functions of the bones and ligaments of the foot are given free play and the muscles of the foot will be strengthened. Other objects and features of the invention will be pointed out hereinafter.

Accordingly the invention is embodied in an insole constructed and designed as hereinafter set forth and as illustrated in the accompanying drawing in which

Fig. 1 is a phantom diagrammatic view showing the insole in longitudinal section in position with relation to the foot and the shoe, the latter and the foot being shown in simple outline with the bones of the foot.

Fig. 2 is a top view of the insole.

Fig. 3 is a cross sectional view taken on the line 3—3 of Fig. 1 through the foreward part of the insole.

Fig. 4 is a similar view on the line 4—4 of Fig. 1 through the shank portion of the insole.

Fig. 5 is a cross sectional view through the heel portion of the insole on the line 5—5 of Fig. 1.

In Fig. 1 the shoe is indicated by the outline 6. The foot is represented by the outline 7. The bones of the foot are shown in outline in substantially correct anatomical relation. The insole according to this invention consists of a relatively hard portion 8 and a relatively softer portion 9, the two portions forming a one piece insole. The rear portion 8 is formed with a heel seat 10 from which extends upwardly a heel surrounding cupping wall 11. The object of this formation is to provide a firm heel gripping portion or heel cup to keep the adipose (fat) pad underneath the heel bone 12 confined and restricted to its natural position whereby to prevent the adipose tissues from spreading or being pushed aside outwardly to the sides of the heel. The heel cupping wall 11 is designed to retain the natural contour of the heel at the back and the sides of the heel bone 12 as indicated by the dotted line 13 which illustrates the upper side edge of the heel cup formation and which slopes gently forward and merges

5 with the shank 14 of the insole. When the adipose tissues are pushed aside or spread, the heel bone will press directly down upon the underlying skin and cause sensitivity and pain. When the heel in its entirety is firmly held by the heel cup as herein provided in the natural position of the heel, the foot is prevented from sliding forward in the shoe and the adipose heel pad is confined to its natural position.

10 The insole is curved upward and around the heel and the sides of the foot to a point just behind the heads of the first and fifth metatarsal bones, 15 and 16 respectively, so that there are no sharp edges to irritate the soft tissues of the 15 plantar (bottom) surface of the foot. The curvature of the sides of the insole conforms to the form of the foot and merges with the shank portion 14 as shown at 17 in Fig. 4 on the medial side of the foot. The portion of the insole which lies underneath the longitudinal arch of the foot is shaped to conform to the natural contour of the foot arch which is composed of the tarsal and metatarsal bones. Thus there is no space between the arch of the foot and the shank of the insole such as may be found in ordinary shoes. Inasmuch as the rear portion of the foot from the metatarsal heads to the heel bone requires a firm support, the rear portion of the insole including the shank portion, that is the portions 8 and 14 respectively, are made of a relatively hard or firm material, for example cork or other moldable substance may be used. Such substances or material are sold under different trade names and are characterized by being resilient or yielding to only a very limited degree.

35 The forefoot portion 9 of the insole lies under the metatarso-phalangeal joints and the phalanges (toe bones). It extends forwardly of the tarso-metatarsal portions of the insole. The greater part of foot disturbances and foot troubles 40 occur in the metatarso-phalangeal area (the forward portion of the foot) because the only freely movable joints of the foot are the metatarso-phalangeal joints and the interphalangeal joints. 45 For these reasons, these joints according to this invention, rest upon an uninterrupted resilient yielding support, namely the forward insole portion 9 instead of upon a relatively hard surface having distinctly defined sharp perimetral edges 50 such as are found in ordinary shoes. An uninterrupted yielding insole support under this portion of the foot permits a natural movement of the bones of the foot and prevents corns, calluses and other growths under these joints, particularly under the first and fifth metatarso-phalangeal

joints and the interphalangeal joints of the first digit (toe) and the external lateral side of the fifth digit (toe) which otherwise usually extend over or ride over the perimetral edges of the ordinary insole.

The shank portion 14 connects the heel portion with the toe portion of the insole. The portion 14 is integral with the heel seat portion 10 and the joint between the two insole portions 8 and 9 is curved forwardly as shown by the lines 20, 21 to conform to the plantar aspects of the shafts of the metatarsal bones. The joining surface 22 is rearwardly inclined and by reason of its curvature, strain and fatigue of the tissues connecting the bones of the metatarsal area, are prevented. The joint between the portions 8 and 9 may be made in any suitable manner by any suitable joining means such as adhesive. The forward portion 9 is made of a resiliently yielding material, for example, nitrogen gas-filled cellular rubber may be used.

The dimensions of the insole, particularly of the portion 9, are such that the insole extends beyond the outlines of the foot so that under weight bearing all the metatarso-phalangeal joints settle down in the same plane upon the resilient support 9 and the first and the fifth metatarso-phalangeal joints are afforded space for natural movements and are not pushed into an upper plane. The relation between the insole and the upper of the shoe is shown in Fig. 3 where the upper is indicated at 25 and the insole edges 26 extend clear to the upper and therefore beyond the perimetral outline of the foot.

The insole according to this invention is characterized by the property of holding and supporting the metatarsal shafts in their normal positions without employing upward pressure and allows the metatarso-phalangeal joints to drop gently into a yielding resilient cushion 9 of cellular rubber or like substance thereby alleviating shocks and irritation to the bones involved. During the natural function of the bones of the foot under weight bearing, the phalanges, resting on the resilient surface, will grip into the resilient support and thereby strengthen the muscles of the foot.

As illustrated in Fig. 1 the insole according to this invention is not intended as a sole element

to be placed within a finished shoe in the manner in which separate loose insoles or foot supports are customarily placed within a shoe. The reason for not using the herein disclosed insole as a separate loose insole is that thereby the vertical available space for the foot within the shoe is diminished and hence the full comfort of the insole element as an integral part of the shoe is not realized as planned.

10 I claim:

An inner sole for a shoe consisting of a heel and arch supporting section of mildly yielding material having its forward portion terminating in a forwardly and downwardly inclined curved edge, a forward ball and toe section of soft yielding material terminating in a rear portion having a rearwardly and upwardly inclined edge complementary to and matching the said edge of the heel and arch supporting section, adhesive applied to the said two edges to join the said two sections to form an inner sole for a shoe, said heel and arch supporting section being curved longitudinally and transversely and extending under and in complete contact with the plantar aspects of the heel bone and mid-tarsal bones of the foot, said ball and toe section extending under the metatarso-phalangeal joints and in upwardly curved abutment with the sides of the shoe upper, said joined edges being curved laterally in conformity with the plantar aspects of the metatarsal phalangeal joints of the foot.
